UNITED STATES PATENT OFFICE.

JAMES P. GRANT, OF BERKELEY, CALIFORNIA.

GRINDING ATTACHMENT FOR BICYCLES.

No. 875,806.

Specification of Letters Patent.

Patented Jan. 7, 1908.

Application filed May 21, 1907. Serial No. 374,873.

To all whom it may concern:

Be it known that I, JAMES P. GRANT, a citizen of the United States, residing at Berkeley, in the county of Alameda and State of California, have invented certain new and useful Improvements in Grinding Attachments for Bicycles, of which the following is a specification, reference being had therein to the accompanying drawing.

10 This invention relates to improvements in grinding devices, and has for its object the provision of means for facilitating the rotation of a grinding element detachably supported upon a bicycle frame.

15 Another object of the invention is the construction of a grinding attachment for bicycles, which comprises a minimum number of parts, is simple in operation, and comparatively inexpensive to construct.

20 With these and other objects in view, the invention consists of certain novel constructions, combinations, and arrangements of parts, as will be hereinafter fully described and claimed.

25 In the drawings: Figure 1 is a view in side elevation, of an attachment constructed in accordance with the present invention, and showing the same secured to a bicycle frame.

30 Fig. 2 is a plan view of the grinding-wheel or element supporting device, while Fig. 3 is a plan view of the driving-member supporting device through the medium of which the grinding-wheel is driven or rotated. Fig. 4 is a view, in side elevation, of the arm carrying 35 the belt-tightening pulley. Fig. 5 is a view in side elevation of the auxiliary clamp, upon which is supported the shaft carrying the friction wheel and the rear pulley.

Referring to the drawings by numerals, 1 40 designates the front, guiding post of an ordinary bicycle frame, and 2 the rear forks or seat posts. The horizontal bar 3 connects the front and rear posts 1 and 2.

45 My improved grinding attachment comprises a pair of devices, one of which carries the grinding wheel and the other a friction wheel and driving-pulley, through the medium of which the grinding-wheel is rotated. In the following description, I shall refer to 50 the device carrying the grinding-wheel or member as the grinding-wheel supporting device, and to the rear device carrying the driving-member as the driving-member supporting device, to facilitate the description of 55 my attachment.

The grinding-wheel supporting device comprises a clamp 4, which is composed of clamp-members 5 and 6. Each of these members 5 and 6 is provided at its outer end with a curved portion 7, constituting a socket upon 60 the clamp 4, within which is positioned the front post 1. The horizontal bar 3 is positioned between the clamp-members 5 and 6, as clearly seen upon referring to Fig. 2. A block 8, constituting an enlarged portion 65 upon the clamp-member 5, is secured to said clamp-member 5, and a screw-threaded bolt or screw 9 extends through the clamp-member 6 near its inner end, and is threaded through the clamp-member 5 into block 8. 70 Between the outer ends of the clamp-members 5 and 6 and bolt 9, is another screw-threaded bolt or screw 10, which bolt 10 extends through member 4 and is threaded, preferably, through the clamp-member 5. Through 75 the medium of bolts 9 and 10, the clamp-members are secured upon the post and bar 1 and 3, respectively.

The block 8 is provided with, preferably, a longitudinally-extending aperture, within 80 which is adjustably and detachably secured a shaft 11. The shaft 11 is secured in an adjusted position upon block 8 through the medium of thumb-screw 12. The thumb-screw 12 is threaded into block 8 and engages, at its inner end, the shaft or supporting-bar 11. A spindle or axle 13 is secured near the upper end of shaft or bar 11, and journaled upon this axle 13 is a grinding-wheel 14 and a belt-pulley 15. 90 The wheel 14 and pulley 15 are keyed against independent, rotary movement upon shaft 13.

The thumb-screw 13 is screw-threaded upon its shank throughout its length, and upon the shank is threaded a thumb-nut 16, 95 between which nut 16 and block 8 is positioned a detachable arm 17, which arm is curved throughout its length, see Fig. 4, and is bent inwardly, as at 19, and journaled upon the extreme upper end, is a belt-tightening pulley 20. The lower end of the arm is, preferably, slotted or bifurcated, as at 21, so that the same may be easily removed off of block 8 by loosening the clamp thumb-nut 16, or said arm may be adjusted to keep the 105 endless belt 22 tight.

The driving-member supporting device comprises a clamp 23. This clamp comprises a substantially U-shaped body 24, which is formed, preferably, from a single 110

piece of resilient metal, the ends of which piece are bent back parallel with the remaining portion of the body for constituting reinforcing means for said body, the extreme 5 ends of the body being slightly outwardly curved, as at 25, constituting braces, which are engaged by the shaft 26, extending through the body 24, see Figs. 3 and 5. The body 24 is enlarged, at its end 27, and a 10 thumb-screw 28 is threaded through the enlarged portion 27 of the U-shaped body, the inner end of said screw 28 engaging the shaft or bar 26 for locking the same in an adjusted position, whereby the frictional-wheel 29, 15 carried by axle or bolt 30, may be retained in frictional contact with the rear wheel 31 of the bicycle. Fixedly secured to the frictional wheel or roller 29, is a pulley 32. The belt 22 is carried by pulleys 15 and 32, and 20 said belt is retained tight or taut upon said pulleys through the medium of the tightening-pulley 20.

The rear forks 2 are positioned between the sides of the U-shaped body 24, and are 25 clamped by said sides by extending thumb-bolt 33 through one of the sides and threading it into the opposite side, see Fig. 3. Through the medium of the thumb-screw 28, and the braces 25, the shaft or bar 26 can be 30 retained in a rigid position upon the rear clamp 23, while the shaft or bar 11 carrying the grinding-wheel can be adjusted to suit the height of the operator, and securely fastened in the adjusted position.

35 From the foregoing description, it is to be noted that my grinding attachment comprises a front clamping-device, carrying a grinding-wheel and a pulley, and a rear clamping-device, carrying a friction-wheel 40 and pulley, the pulleys of the two devices being connected by an endless belt.

What I claim is:

1. In a grinding attachment for bicycles, the combination of a clamp provided with a 45 block, a shaft adjustably mounted upon said block, means carried by said block and engaging the same and securing the shaft in an adjusted position, a grinding-wheel carried by said shaft, a pulley fixedly secured to said 50 grinding-wheel, a friction-wheel supported contiguous to said grinding-wheel, and means connecting said friction-wheel and grinding-wheel, whereby, when rotary movement is 55 imparted to said friction-wheel, similar movement will be imparted to said grinding-wheel.

2. In a grinding attachment, the combination of a clamp, a block secured to said clamp, a grinding-wheel carried by said 60 block, a pulley secured to said grinding-wheel, a friction-wheel positioned contiguous to said grinding-wheel, a pulley fixedly secured to said friction-wheel, a belt mounted upon said pulleys, an arm provided with a 65 lower, bifurcated end engaging said block,

means adjustably securing said arm to said block, and a tightening pulley carried by said arm and engaging said belt for retaining the same in a tight condition.

3. A grinding attachment for bicycles, 70 comprising a clamp provided with a substantially U-shaped, resilient body having portions bent back parallel therewith and the extreme outer ends of said bent-portions turned outwardly and constituting braces, 75 a shaft extending through said body and engaging said outwardly turned ends, means for securing said shaft in an adjusted position upon said body, a driving-member carried by said shaft, a driven-member positioned contiguous to said driving-member, and means connecting said driving-member and driven-member, whereby, when movement is imparted to said driving-member, similar movement will be imparted to said 85 driven-member.

4. In a grinding attachment for bicycles, the combination with a frame, of a pair of clamps supported upon said frame, each clamp positioned upon a plurality of bars of 90 said frame, a driving-member adjustably mounted upon one of said clamps, means securing said driving-member in an adjusted position, a driven-member adjustably mounted upon the other clamp, means for securing said driven-member in an adjusted 95 position upon said clamp, and means connecting said driving-member and driven-member, whereby movement of one of said members will impart similar movement to 100 the other member.

5. In a grinding attachment for bicycles, the combination of a clamp, provided with a substantially U-shaped, resilient body, means for clamping said body upon an object, a shaft adjustably mounted upon said body, means for securing said shaft in an adjusted position upon said body, a friction-wheel carried by said shaft, and a pulley carried by said shaft and fixedly secured 110 against independent, rotary movement with respect to said friction-wheel.

6. The combination with a bicycle frame, of a clamp engaging said frame, said clamp provided with parallel sides, means extending transversely of said sides and adapted to draw the same together for clamping said frame, a shaft engaging and slidably mounted upon said clamp, locking means for securing said shaft in an adjusted position, and a 120 friction-wheel and a pulley carried by said shaft.

7. In a device of the character described, the combination with a support, of a single-piece clamp provided with a body portion 125 and with portions bent back parallel to said body portion, means extending through said body portion and said parallel portions for drawing the sides of the body portion and the parallel portions together, a friction- 130

wheel and a pulley, and means supporting said friction-wheel and pulley upon said clamp.

8. In a grinding attachment for bicycles,
5 the combination of a clamp, comprising a pair of clamp-members, one detachably secured to the other member, a shaft positioned contiguous to one of said members, means detachably and adjustably securing
10 said shaft to said member, a grinding-wheel

and a pulley positioned contiguous to said shaft, and means rotatably securing said grinding-wheel and pulley to said shaft.

In testimony whereof I hereunto affix my signature in presence of two witnesses.

JAMES P. GRANT.
